US0D1028399S

(12) **United States Design Patent** (10) **Patent No.:** **US D1,028,399 S**
(45) **Date of Patent:** **** May 21, 2024**

(54) **ROBOTIC CLEANER**

(71) Applicant: **Anker Innovations Technology Co. Ltd.**, Changsha (CN)

(72) Inventor: **Chao Ren**, Shenzhen (CN)

(73) Assignee: **Anker Innovations Technology Co., Ltd.**, Changsha (CN)

(**) Term: **15 Years**

(21) Appl. No.: **29/797,478**

(22) Filed: **Jun. 30, 2021**

(30) **Foreign Application Priority Data**

Jan. 13, 2021 (CN) 202130023468.3

(51) **LOC (14) Cl.** **15-05**

(52) **U.S. Cl.**

USPC **D32/31; D32/21**

(58) **Field of Classification Search**

USPC D32/15, 21, 23, 25, 31–34, 16
CPC .. A47L 2201/00; A47L 2201/02; A47L 11/10;

A47L 11/24; A47L 11/4011

(57) **CLAIM**

The ornamental design for a robotic cleaner, as shown and described.

DESCRIPTION

FIG. 1 is a front perspective view of a robotic cleaner showing my new design; and,
FIG. 2 is a top view thereof.

The broken lines depicting the remainder of the robotic cleaner form no part of the claimed design.

1 Claim, 2 Drawing Sheets

FIG. 1

FIG. 2
